UNITED STATES PATENT OFFICE.

WILLIAM M. HALLBAUER, OF ST. LOUIS, MISSOURI, ASSIGNOR OF ONE-HALF TO
EDWARD D. HOLTHAUS, OF ST. LOUIS, MISSOURI.

STORM-WINDOW FOR STREET-CARS, LOCOMOTIVE-CABS, AND THE LIKE.

1,042,671.

Specification of Letters Patent.

Patented Oct. 29, 1912.

Application filed January 22, 1912. Serial No. 672,580.

To all whom it may concern:

Be it known that I, WILLIAM M. HALLBAUER, a citizen of the United States, residing at Wellston, in the city of St. Louis and 5 State of Missouri, have invented certain new and useful Improvements in Storm-Windows for Street-Cars, Locomotive-Cabs, and the Like, of which the following is a specification.

10 My invention relates to storm windows particularly adapted for use in the storm fronts of street cars and has for its object the provision of a hoodlike attachment mounted in the front window casing and 15 having an inclined portion to catch rain, snow, ice, etc., and an inclined transparent plate under the first-mentioned inclined portion through which the motorman gets his view of the roadway ahead, said transparent 20 plate being mounted in a frame removably secured in the hood frame so that it can be taken out and reversed when it is desired to clear it of ice or snow.

My invention furthermore consists in providing a hood that is capable of adjustment to accommodate it to the height of the motorman so that the inclined transparent plate 25 will be opposite his eyes.

My invention will be described in detail 30 hereinafter and illustrated in the accompanying drawings, in which—

Figure 1 is a front view of a street car storm front showing my improved window in position, Fig. 2, a side view, Fig. 3, a 35 horizontal sectional view of the window, Fig. 4, a cross section with the removable frame displaced, Fig. 5, a similar view with the removable frame in position, Fig. 6, a detail view of the removable frame, and 40 Fig. 7, a detail view of the latch mechanism. Fig. 8 is a detail view of certain parts of the device.

In the drawings similar reference characters will be used to designate corresponding 45 parts in the several views.

A indicates the storm front of a street car having the central window frame B through which the motorman looks while operating his car. In the usual construction of storm 50 fronts a sliding sash C is mounted in frame B which may be opened in warm weather, and closed when the weather is rough and stormy. The window affords protection to

the motorman but when it rains, or hails, or 55 snows the vision through the window is obstructed and sometimes becomes so bad that it is necessary for the motorman to open the window to enable him to see, and the usefulness of the storm front is nullified.

My invention consists in the provision of 60 a device for attachment to the window frame by which the motorman is enabled to see ahead in any kind of weather without exposing him to its discomforts.

To this end my invention consists of a 65 hood formed of any suitable rigid material preferably sheet metal, and having an open rectangular frame 2, in which is secured a plate of transparent material 2^a, such as glass, and with triangular shaped plates 3 70 secured to, or formed integral with, its ends, said end plates 3 having outwardly extending flanges 4 on their longer sides, and inwardly extending flanges 5 on their shorter or lower sides. The flanges 4 on the longer 75 sides slidably engage strips 6 secured to the sides of frame B so that the hood may be raised or lowered as desired and a suitable fastener such as shown at 7 is utilized to hold the hood in adjusted position. 80

The upper side of rectangular frame 2 is curved in cross section as shown and provided with a lining of sheet rubber or other suitable material, as at 8, that engages the storm front above the window frame B in 85 a weather tight manner. The lower bar of rectangular frame 2 is formed with an inwardly extending flange 9 that together with flanges 5 on the end plates 3 form rests for a removable frame 10 having a transparent 90 plate 11 mounted therein.

Frame 10 is provided with pins or lugs 12 on its ends, and the inner sides of plates 3 with projections 13 having notches 14 therein to engage the pins or lugs 12, and 95 the inner sides of frame 2 with projections 15 that engage the upper side of frame 10 when in position.

16 indicates leaf springs secured to the lower rail of frame 2 that engages the edge 100 of frame 10 and normally tends to move the pins or lugs 12 into engagement with the notches 14. By this construction it will be apparent that the frame 10 may be quickly removed, reversed and replaced, so that 105 should the outer side of the transparent

plate 11 become covered with rain, or snow, or ice the frame 10 may be taken out and replaced in a reversed position and the obstruction removed.

5 In operation the hood is mounted on the storm front of a car, as shown in the drawings, and when in position the frame 2 and plate of transparent material 2^a act as a shield to catch rain, snow or hail, while the 10 motorman looks through the transparent plate 11 in the frame 10, which, as shown, inclines inwardly and slightly downwardly from the lower edge of frame 2, the inner edge of the frame 10 engaging the top of the 15 window sash C which is lowered, as shown, and secured in position under the frame 10 to form a weather tight front. As stated above the frame 10 may be removed and reversed and replaced when vision there- 20 through becomes obscured by ice or snow ad-hering to it.

I have described my invention as applied to the storm fronts of street cars, but it may be applied to locomotive cab windows, mo- 25 tor vehicles and the like with little or no alteration so that I do not limit myself to the application of my invention to street cars, except where specifically claimed hereinafter.

Having thus described my invention what I claim is—

1. In a storm window, a hood frame having end plates with inwardly extending flanges, notched projections on said end plates, and a sash frame having pins or lugs 35 on its ends, said sash frame being adapted to seat on the flanges aforesaid and the pins or lugs to engage said notched projections.

2. In a storm window, a hood frame having a front plate and end plates with in- 40 wardly extending flanges, notched projec-tions on said end plates, projections on said front plate, a sash frame adapted to seat on said flanges and under the projections on the front plate, pins or lugs on the ends of said 45 sash frame and adapted to engage the notched projections on the end plates, and springs secured to the front plate and adapt-ed to engage the sash frame to hold said pins or lugs in engagement with the notched pro- 50 jections aforesaid.

In testimony whereof I hereto affix my signature in the presence of two witnesses.

WILLIAM M. HALLBAUER.
